MEANS FOR FACILITATING REMOVAL OF
COVER STRIPS OF FROST SHIELDSHarry C. Atwood, Minneapolis, Minn., assignor to
Durkee-Atwood Company, Minneapolis, Minn.,
a corporation of Minnesota

Application August 18, 1937, Serial No. 159,674

2 Claims. (Cl. 20—40.5)

This invention relates to improvements in frost shields, or clear vision shields, of the dead-air-space type, ordinarily comprising a piece of glass or other transparent material having spacer and sealing strips adhesively secured thereto in dead-air-space-forming relation. The glass is usually rectangular and the spacer strips are overlapped at the corners. The outer faces of the spacer strips are covered with tacky adhesive, and cover strips such as Holland cloth are removably held by the tacky adhesive, said cover strips being thus adapted for stripping off to expose the adhesive so that the shield may be attached by merely pressing these adhesively coated surfaces against the wind shield.

An object of the invention is to provide means whereby removal or stripping of these cover strips will not destroy the sealed relation between the spacer strips and the glass.

The spacer and sealing strips in these devices are generally four in number and the ends of these strips are sealingly overlapped, with or without mitering, at the corners of the rectangular plate. Heretofore, it has been necessary for the user, to gain access to the ends of the cover strips by putting the thumb nail or finger nail under the cover strips, at the corners, to raise them sufficiently to be held between the thumb and forefinger while stripping by motion from the end toward the middle of the spacer strip. This has resulted in pulling of the spacer strips away from the glass plate, thus destroying the seal which is essential to the anti-frosting function of the shield.

The present invention provides means whereby the cover strips can be unfailingly removed without destroying the seal.

Features of the invention include all types of construction shown, along the broader ideas of means inherent in the disclosure.

Figure 1 is a face view of a frost shield illustrating one embodiment of my invention;

Figure 2 is a cross section through the pull-up tab, on line 2—2 of Figure 1;

Figure 3 is a longitudinal section on line 3—3 of Figure 1;

Figure 4 is a perspective view showing how one form of my invention acts on the inner ends of the cover strips to accessibly position them to be stripped by motions towards their outer ends;

Figure 5 is an enlarged view showing the overlapped relation of the spacing and sealing strips at the corner;

Figure 6 is a transverse section similar to Figure 2 showing how the invention is applied to a sealing strip of ordinary structure; and

Figure 7 shows a modification of the means associated with the inner ends of the strips to facilitate access by the fingers for stripping outwardly toward the corners of the shield.

Objects, features and advantages of the invention will be set forth in the description of the drawing, and in said drawing,

Numeral 1 indicates a polygonal, in this case rectangular, sheet of transparent material such as glass having combined spacer and sealing strips 2 adhesively secured thereto by adhesive, not shown. Numeral 3 indicates a cover strip which is ordinarily made of Holland cloth, and which is held to the spacer strip by usual tacky adhesive, not shown.

My invention includes the use of these cover strips for each spacer and sealing strip. The inner ends of the cover strips of each spacer strip are disposed about midway of the ends of the spacer strip and there is associated with the inner ends of each pair of cover strips means to facilitate access of these ends by the fingers, whereby each cover strip may be stripped by a motion toward the outer end and toward the corners of the shield. In this instance the overlapping of the spacer strips is by mitering but overlap may be had in other ways. The point is that stripping from the outer ends toward the middle is objectionable for the reasons before mentioned. In Figures 1, 2, 3, 4 and 6 is shown one embodiment of means for facilitating access by the fingers and it comprises a tab 10 of cover material which is interposed between the cover and the sealing strips as shown, and which projects laterally as at 11 to be grasped by the thumb and finger so that it can be pulled upwardly as shown in Figure 4 whereby to correspondingly raise the inner ends 14 of the cover strips, whereafter by grasping an end between thumb and forefinger it can be stripped away from the middle towards the overlapped ends of the spacer strips, thereby positively preventing any corner loosening of the spacer strips to destroy the dead-air-sealing function.

The tab 10 or its equivalent can be applied at the corner, and the claims are intended to cover its application at that point to facilitate lifting. The preferred form of the invention is however the use of two cover strips to each spacer strip.

Figures 1 to 5 inclusive show a special form of strip which is not claimed herein but which because of its structure is particularly liable to be pulled away from the glass or injured under conditions where it is necessary to start stripping of the cover strips inwardly from the

- corners. This strip is cross sectionally rectangular and the two opposite faces 16 of greatest area are adapted respectively to be attached one to the glass 1 and the other to the wind shield.
- 5 5
- 5 Inwardly from each face 17 the material is slitted as at 18, the slits extending substantially more than half way through the material. The slits are parallel to one another and to the faces 16. This form of strip is covered in a co-pending 10 application to another inventor now Patent No. 2,111,843, granted Mar. 15, 1938, and is of course not claimed herein. However, the present invention has a special application to this form of strip because its structure is such that it might be 15 more easily torn or injured when an attempt is made to remove cover strips, by putting thumb nail under the strips at the corners.

In Figure 6 any ordinary form of strip is intended to be indicated at 2a because, whatever 20 form of strip is used, the old scheme of beginning stripping at the corners is, when the thumb nail is depended upon, obviously objectionable.

In Figure 7 is shown a modification of means 25 associated with the inner ends of the cover strips for facilitating access by the fingers for stripping. In this case instead of using the interposed tab 10 the ends of the strips 3 are widened to provide laterally projecting portions 20 one for the end of each strip. As shown in the drawing, the ends 30 of the cover strips are overlapped merely to facilitate their application in covering position. It is of course obvious that the inner ends of the cover strips could be abutted and that their outer surfaces, at the joint, could be coplanar, as shown 35 in Figure 3. The laterally projecting portions 20 facilitate access by the fingers. It is understood that this embodiment can be applied at the corners also.

I believe myself the first to conceive of the idea

of stripping outwardly from any point which is intermediate of the ends of a spacer strip, for the purpose of avoiding the difficulty mentioned herein, and also believe myself the first to associate any means with the strips, either at the corners and in the region of the overlap of the spacer strips, to facilitate stripping without breaking of the seal, in a frost shield structure of the dead-air-space type. My invention prevents breaking of the seal, and that is the gist of it. 10 Therefore, I consider the expression "means associated with" to refer to any and all means which may be used for this purpose.

I claim as my invention:

1. A frost shield comprising a transparent plate, 15 spacer-and-sealing strips secured thereto by adhesion and having a free adhesive surface, cover strips joined end to end on said spacer-and-sealing strips, and removably held thereto by said adhesive surface, and means for lifting the adjacent ends of said cover strips from the sealing-and-spacer strips, comprising a tab of cover strip material, said tab being secured to the spacer-and-sealing strip beneath the adjacent ends of said cover strips in a position to be overlapped by the ends of said cover strips.

2. A frost shield comprising a transparent plate, spacer-and-sealing strips secured thereto by adhesion and having a free adhesive surface, cover strips joined end to end on said spacer-and-sealing strips, and removably held thereto by said adhesive surface, and means for lifting the adjacent ends of said cover strips from the sealing-and-spacer strips comprising a tab of cover strip material having an overhanging grip portion secured to the spacer-and-sealing strip beneath the adjacent ends of said cover strips in a position to be overlapped by the ends of said cover strips.

HARRY C. ATWOOD.
